UNITED STATES PATENT OFFICE.

CHARLES KLOEPFER, OF NEW YORK, AND CLARENCE C. KLOEPFER, OF BROOKLYN,
NEW YORK.

EXTENSION STEP-LADDER.

1,283,212.

Specification of Letters Patent.

Patented Oct. 29, 1918.

Application filed May 29, 1916. Serial No. 100,434.

To all whom it may concern:

Be it known that we, CHARLES KLOEPFER, a citizen of the United States, residing in the city of New York, borough of Queens, 5 in the county of Queens and State of New York, and CLARENCE C. KLOEPFER, a citizen of the United States, residing in the city of New York, borough of Brooklyn, in the county of Kings and State of New York, 10 have invented a certain new and useful Improvement in Extension Step-Ladders, of which the following is a specification.

The invention relates to step-ladders having two portions arranged to be swung 15 apart or spread at the base, and the object of this invention is to provide a ladder of this type in which the portions may be thus set on a level surface and also stand firmly on adjacent surfaces of different heights, 20 as upon separated treads of a flight of stairs, or in which the two portions may be slid one upon the other to condition the ladder for service as a single element of adjustable length, or the two portions separated 25 for service as two independent short ladders, and which shall be strong and reliably braced and supported under all conditions, and may be easily operated and economically manufactured.

30 The invention consists in certain novel features and details of construction and arrangement by which the above objects are attained, to be hereinafter described and claimed.

35 The accompanying drawings form a part of this specification and show the invention as it has been carried out in practice.

Figure 1 is a perspective view showing the portions connected and spread for service as a step-ladder.

Fig. 2 is a corresponding side elevation of the upper parts.

Fig. 3 is a side view showing the portions collapsed.

45 Fig. 4 is a corresponding front elevation.

Fig. 5 is a vertical section on the line 5-5 in Fig. 4.

Fig. 6 is a horizontal section on a larger scale, taken on the line 6-6 in Fig. 2.

50 Fig. 7 is a horizontal section on the line 7-7 in Fig. 2, and partly in plan view.

Fig. 8 is an angular section taken on the line 8-8 in Fig. 5, seen in the direction

indicated by the arrows, and partly in under-plan view.

Fig. 9 is a horizontal section on the line 9-9 in Fig. 3.

Fig. 10 is a plan view, partly in horizontal section on the line 10-10 in Fig. 3.

The succeeding figures are incomplete side 60 elevations on a greatly reduced scale, showing the ladder in various conditions of service.

Fig. 11 shows the two portions extended as a single ladder.

Fig. 12 shows the portions connected and spread and resting upon a flight of stairs.

Fig. 13 is similar to Fig. 11 but with the removable top platform in place.

Figs. 14 and 15 show the two portions 70 separated and each serving as an independent short ladder.

Similar letters of reference indicate the same parts in all the figures.

The ladder comprises two main sections 75 or portions A and B which for convenience of description will be termed front and rear portions respectively, and a removable top-step or platform C and shelf D.

The front portion A is shown as provided 80 with steps A² equally spaced and secured to the side rails A¹ A¹, the latter each having a longitudinal slot a extending nearly the whole length, and at the top the rails are cut at an angle to match to the adjacent 85 edges of the rails B¹ of the rear portion B. At the bottom the rails A¹ carry angularly disposed legs A³ A³ extending therethrough from the lowermost step and serving to increase the lateral stability by offering a wide 90 base.

The rear portion B is preferably somewhat longer than A and is provided with rungs B² set in the rails B¹ and corresponding with the steps A², except at the top 95 where the rung is preferably displaced by a narrow step B³. The rails B¹ extend beyond the step B³ and on the inner faces of their ends are sockets C² receiving rods or standards C¹ on which is mounted the 100 platform C. The latter may be removed by lifting it and drawing its rods out of the sockets, and the platform may be reversed to overhang oppositely to the position shown in Figs. 1 and 2.

105 On the inner edge of each rail B¹ is se-

cured a strip B^4 of angle-iron having its projecting flange perforated at intervals, as at b , to receive the outer ends of bolts F carried by the portion A and serving to connect both portions pivotally at their upper ends. Thus joined the portions may be swung apart or spread at the bottom as in Figs. 1 and 2, or collapsed to lie in parallel planes as in Figs. 3, 4 and 5.

- 10 The lower ends of the portions are held in the collapsed condition by spring-arms J secured to the rails B^1 B^1 and each having an inturned finger J^1 adapted to engage the slot a in the adjacent rail A^1 .
 15 In releasing the rails A^1 the arms J are sprung forcibly outward sufficiently to disengage the fingers J^1 from the slots; a head J^2 formed by bending the material of the arm offers a convenient means for thus moving the arm.

20 In order to insure against accidental release of the arms J , J , a shorter stiff plate J^3 is attached to the rail B^1 near the arm J and carries a turn-button J^4 adapted to overlap upon and thus engage the outer face of the arm J and prevent its outward movement until released.

25 Springs bars A^4 A^4 mounted on the rails A^1 A^1 extend across the rails B^1 B^1 close to their outer faces and are each provided with a pin A^5 adapted to lie adjacent to the rear edge of the rail B^1 and aid in holding the portions together when the bolts F are withdrawn, and with the arms J , serve as guides 30 for the portions when the latter are slid one upon the other in extending the ladder, as indicated in Figs. 11 and 13 and by the dotted lines in Fig. 3.

35 D is a removable folding shelf adapted to support a pail or other article; it is mounted on side-bars D^1 D^1 each notched at the mid-length to receive and rest upon one of the rungs B^2 and having a pivoted catch D^2 by which the engagement with such rung may be securely effected while permitting the arms and shelf to be partially rotated thereon as in folding. When the portions A and B are spread as in Figs. 1 and 2, the side-bars D^1 D^1 extend across the space between 40 the rails A^1 B^1 and overlap the inner faces of the rails A^1 , and each carries on its outer face a pivotally attached link D^3 having a stud D^4 adapted to engage in an opening e in a plate E attached to the inner face of the rail A^1 , as shown in Figs. 2 and 7, thus joining the two portions, and to insure stability 45 of the shelf a turn-button D^5 is mounted on the lower face of each bar D^1 adapted when turned to overlap the under edge of the adjacent link D^3 and prevent a buckling movement of the latter relatively to the bar D^1 .

50 G G are folding braces each in two parts pivotally joined and pivotally attached to the rails A^1 A^1 . The outer end of each is

hook-shaped, as at G^1 , to engage one of the 65 rungs B^2 ; when thus engaged the ladder may be opened or closed without breaking the engagement, the braces folding upon themselves in the usual manner. When the ladder is conditioned as in Fig. 12 for service on stairs or other stepped surfaces, the braces G G may be engaged with a higher rung.

70 The bolts F F are carried in a housing F^1 on the under face of the uppermost step A^2 ; 75 the outer ends are guided in thimbles F^2 on plates F^3 attached to the rails A^1 A^1 , and the inner ends in loops F^4 on the housing. Between each loop and a collar F^5 on each bolt, is a spring F^{11} tending to force the bolts outwardly into engagement with the holes b in the flanges of the strips B^4 . On the inner end of each bolt, within the housing, is a slotted arm F^6 , each extending at a right angle to its bolt and opposite to each other, and the slots receive pins F^7 set in opposite ends of a lever F^8 arranged to swing on a pivot F^9 and having a handle F^{10} , see Fig. 8, by which it may be turned. When the bolts are in the engaged position they are 80 in line with the pins F^7 and pivot F^9 and are thus held reliably; when it is desired to withdraw the bolts for engagement in other holes of the series or to separate the portions A and B , the lever F^8 is turned, as shown by 85 the dotted lines in Fig. 8, and the action of the pins upon the arms F^6 retract the bolts in opposition to the force of the springs F^{11} .

90 The bolts F F serve as pivots upon which the portions A and B may be swung in 100 spreading or folding, within the limits defined by the angular ends of the rails A^1 A^1 and the length of the folding braces G , G , and when engaged in the uppermost holes b b , as shown, the ladder may be thus opened 105 or closed for general service, and it will be noted that both portions may be utilized for climbing and that when opened the two portions are securely connected by the bolts F F , the bars A^4 A^4 and the folding braces G G . 110

115 When closed the portions may be slid one upon the other by disconnecting the hooks G^1 of the braces from the rung B^2 and withdrawing the bolts F F , the two portions may then be moved relatively to each other to the desired extent, the arms J J and bars A^4 A^4 serving as guides, and the bolts again engaged in a lower pair of holes b . On each rail A^1 is a piece of metal H adapted to ride upon the flange of the strip B^4 and protect 120 the wood of the rail from wear.

125 The shelf D may be removed and replaced as required, and the platform C is as before stated both removable and reversible.

To separate the portions the bolts F F are withdrawn and the bars A^4 forced outwardly to release the upper ends, the spring arms J are then forced out of engagement with the

slots *a*, and the braces *G G* disconnected from the rung *B²*; thus freed each portion may be used independently, the portion *B* still carrying the shelf *D* or with the latter 5 removed, and the portion *B* carrying the platform *D* projecting in either direction as desired, or it may be removed.

Other means for actuating the bolts *F F* may be substituted for the mechanism shown, 10 and certain parts of the equipment may be omitted or modified, or other materials may be employed, in adapting the invention for various purposes and for economy of manufacture.

15 We claim:—

1. An extension step-ladder consisting of front and rear portions, said rear portion having a series of holes in each rail, bolts on said front portion adapted to engage such 20 holes to serve both as pivots and to hold the portions in extended position, the rails of said front portion having each a longitudinally extending slot, and means on said rear portion for separably and slidably engaging 25 such slots.

2. An extension step-ladder consisting of front and rear portions, each having rails, the rails of said front portion each having a longitudinally extending slot, and the rails 30 of said rear portion having each a longitudinally disposed series of holes, bolts on said front portion adapted to engage in oppositely located holes of such series to serve both as pivots and to hold the portions in 35 extended position, arms on said rear portion adapted to engage separably and slidably in such slots, and means for locking said arms in such engagement.

3. An extension step-ladder consisting of 40 front and rear portions each having rails, the rails of said front portion each having a longitudinally extending slot, and the rails of said rear portion each having a longitudinally disposed series of holes, bolts on said 45 front portion adapted to engage in oppositely located holes of such series to serve both as pivots and to hold the portions in extended position, arms on said rear portion adapted to engage separably and slidably in 50 said slots, and bars on said front portion adapted to engage the rails of said rear portion separably and slidably, and arranged to hold said portions in slideable relation when said bolts are disengaged.

55 4. An extension step-ladder consisting of front and rear portions each having rails, the rails of said front portion each having a longitudinally extending slot, and the rails of said rear portion having each a longitudinally disposed series of holes, spring-actuated bolts on said front portion adapted to 60 engage in oppositely located holes of such series to serve both as pivots and to hold the portions in extended position, spring arms

on said rear portion adapted yieldingly to 65 engage in said slots, and spring bars on said front portion adapted yieldingly to engage the rails of said rear portion, said arms and bars arranged to hold said portions in slideable relation when said bolts are disengaged. 70

5. In a ladder of the character set forth and comprising front and rear portions each having rails, the rails of said front portion each having a longitudinally extending slot, a spring arm on each of the rails of said 75 rear portion, and fingers on said arms adapted to engage in such slots, and means engaging said arms to hold the fingers in engagement in said slots.

6. In a ladder of the character set forth 80 and comprising front and rear portions each having rails, the rails of said front portion each having a longitudinally extending slot, a spring arm on each of the rails of said rear portion, fingers on said arms adapted yield- 85 ingly to engage in such slots, plates on the rails of said rear portion adjacent said arms, and means on said plates for engaging said arms and holding said fingers in engagement in said slots. 90

7. In a ladder of the character set forth and comprising a front and a rear portion each having rails, the rails of said front portion each having a longitudinally extending slot, a longitudinally extending strip secured 95 to each of the rails of said rear portion, a flange on said strip, each flange having a series of holes, spring arms on the rails of said rear portion adapted to engage separably and slidably in such slots, oppositely disposed bolts on said front portion adapted to engage such holes to serve both as pivots and to hold the portions in extended position, and means for retracting said bolts. 100

8. In a ladder of the character set forth, a 105 front and a rear portion each having rails, means for separably joining said portions, arms on one portion slidably engaging the other portion, and means pivotally mounted and adapted to overlap said arms to prevent 110 outward movement thereof.

9. In a ladder of the character set forth, and comprising front and rear portions each having rails, steps in said front portion and rungs in said rear portion, arms having 115 notches adapted to engage upon a rung, a shelf on said arms, plates on the rails of said front portion each having holes therein, a link pivoted on the outer face of each of said arms, a stud on each of said links adapted to engage one of such holes and held in engagement with its plate by the adjacent face of its arm, and pivoted means overlapping said link for locking said link and arm against movement relatively to each other. 120

10. An extension step-ladder consisting of front and rear portions, one portion having a series of holes in each rail, bolts on the 125

4
other portion to engage such holes to serve both as pivots and to hold the portions in extended position, the rails of one portion having each a longitudinal slot, and means 5 on the other portion for separably and slidably engaging such slots.

In testimony that we claim the invention

above set forth we affix our signatures, in presence of two witnesses.
